UNITED STATES PATENT OFFICE

2,134,936

MOTOR COMPRESSOR UNIT FOR REFRIGERATING APPARATUS

Robert M. Getchell and Ralph K. Miller, Dayton, Ohio, assignors, by mesne assignments, to General Motors Corporation, a corporation of Delaware

Application October 30, 1928, Serial No. 315,988
Renewed February 24, 1937

6 Claims. (Cl. 230—139)

This invention relates to refrigerating apparatus and more particularly to a mechanical refrigerating system provided with a refrigerant liquefying unit having a rotary refrigerant compressor with a lubricant circulating means.

An object of this invention is to provide a refrigerating system with a refrigerant pump having a lubricant pump drivingly connected to said refrigerant pump, in order to insure positive flow 10 of lubricant as well as of refrigerant.

Another object of this invention is to provide a refrigerant liquefying unit with a rotary pump and with a positive lubricant circulating means provided with a cooling coil for the lubricant.

15 Further objects and advantages of the present invention will be apparent from the following description, reference being had to the accompanying drawings, wherein a preferred form of the invention is clearly shown.

20 In the drawings:

Fig. 1 is a vertical cross sectional view, of the refrigerant liquefying unit, taken along the line 1—1 of Fig. 2, with some parts in elevation.

Fig. 2 is a horizontal cross sectional view, with 25 parts broken away, taken substantially along the line 2—2 of Fig. 1.

Fig. 3 is a diagrammatic view of a refrigerating system embodying features of this invention.

Fig. 4 is a vertical cross sectional view taken 30 along the line 4—4 of Fig. 2.

Fig. 5 is a vertical cross sectional view taken along the line 5—5 of Fig. 2.

Fig. 6 is a vertical cross sectional view of a modified form of refrigerant pump, taken along the line 6—6 of Fig. 7, with the vanes shown in elevation.

Fig. 7 is a cross sectional view taken transversely to Fig. 6.

Fig. 8 is a cross sectional view taken along the 40 line 8—8 of Fig. 7.

Fig. 9 is an elevation of one of the end plates of the pump shown in Figs. 6, 7, and 8.

A refrigerating apparatus embodying features of this invention may include a refrigerant liquefying unit generally designated as 20 and a refrigerant evaporating unit generally designated as 21. The refrigerant liquefied in the unit 20 is conveyed, for instance by a pipe 22, to the refrigerant evaporating unit 21 and is returned by 45 the pipe 23. The pipe 22 may deliver the refrigerant through a fitting 24 which includes a float valve control mechanism, not shown. The pipe 23 may receive the refrigerant from the unit 21 thru the fitting 25. The unit 21 may be of any 50 desired type, for instance of the type described in

the patent to R. G. Osborn 1,556,708 patented October 13, 1925. The refrigerant liquefying unit may be operated by an electric motor 26 which may be connected to the source of electricity 27. The motor may be controlled in its starting and 5 stopping operation by means of a snap switch 28 which may be operated by an expansible bellows 29 connected to the pipe 23.

The refrigerant liquefying unit may comprise a refrigerant pump 30 which discharges compressed or "high side" refrigerant thru the check valve 31 into a lubricant and refrigerant reservoir 32. The reservoir 32 may be connected to a condenser 33, which may include a double spiral coil of finned pipe either in series or in parallel. The condenser 33 may discharge the condensed refrigerant into a circular refrigerant receiver 35. The receiver 35 may be connected to the pipe 22 in order to deliver liquid refrigerant to said pipe. The pipe 23 may be connected to the intake 36 of 20 the refrigerant pump. The pump 30 may be driven by means of a shaft 40 which may pass through the motor 26 and may terminate at its connection with a fan 41. The shaft 40 may be provided with a shoulder 42 which forms a diaphragm type of seal with the bellows 43, which is hermetically attached as by a gasket 43a to a plate 44 which forms part of the pump casing. The seal prevents the passage of refrigerant out past the shaft 40. 30

The shaft 40 is provided with an eccentric offset 45 which is adapted to cause the pumping member 46 to move in a circular orbit. A slidingly pivoted key 47 may be connected to the pumping member 46. The key 47 may be slidingly connected to the cylindrical key-way member 48 which permits the key 47 to reciprocate to a slight extent while swinging about the pivot and also prevents the member 46 from rotating upon its own axis. The key 47 prevents the flow of 40 refrigerant directly from the inlet 36 to the outlet 50. The movement of the member 46 about its orbit in contact with the pump chamber wall 37 pumps the refrigerant from the inlet 36 to the outlet 50 into the reservoir 32. 45

A lubricant circulating system may be provided. For this purpose the reservoir 32 may be partially filled with lubricant, preferably above the top of the plate 51 where the lubricant is subjected to compressor heat. The lubricant from the lower 50 part of reservoir 32 is withdrawn through the passage 52 by means of the pump 53 and is forced through the pipe 54 to a cooling coil 55 whence it is forced through the pipe 56 into the cavity 57 in the shaft 40. The cavity 57 may be connected 55

by means of passages 58 with bearing surfaces such as occur between the off-set 45 and the pumping member 46 or between the end plates 51 or 77 and the shaft 40 of the pump. A passage 59 may be provided in the upper end plate 51 so that lubricant after having been forced into the cavity 57 is discharged through some of the passages 58 and the passage 59 back into the reservoir 32, to provide a constant circulation of the lubricant through the cooling coil 55. The lubricant in this circuit is thus maintained under high side refrigerant pressure throughout.

The pump 53 may be drivingly connected to the refrigerant pump. Thus the key 47 may form the reciprocating plunger of the pump 53. A jacket 60 may be placed around the free end of the key 47. The jacket 60 thus forms a cavity 61, which may be connected by the pipe 52 with the reservoir 32. A check valve 63 may be placed in the passage 52. The cavity 61 may also be connected to the pipe 54. An outwardly directed check valve 64 may be placed in the pipe 54. It will thus be seen that as the member 46 moves in a circular orbit because of the rotation of the shaft 40, that the key 47 is reciprocated. The reciprocation of the key 47 in the cavity 61 pumps the lubricant past the check valve 63 from the reservoir 32, then past the check valve 64 into the pipe 54, and thence to the lubricant cooling coil 55. From thence the lubricant passes through the pipe 56, cavity 57, passages 58 and passage 59 back into the reservoir 32. Thus a closed circuit is formed for the lubricant, said circuit including the bearings of the refrigerant pump, the lubricant pump 53 and the reservoir 32.

The lubricant pump 53 has been shown in Fig. 3 as in a different horizontal plane from the refrigerant pumping member 46. This is for the purpose of diagrammatic showing only, since the pump 53 really is in the same horizontal plane with pumping member 46.

The pumping mechanism heretofore described may be mounted on rubber cushions. Thus rubber cushions 70, which may be cylindrical rubber blocks, may be used. The lower end plate of the pump may include a cup like casing member 71 forming part of reservoir 32 and provided with annular recesses 72 for receiving the cushions 70. The casing member 71 may be connected to the upper end plate 51 by means of bolts 73. The end plate 51 may include an upwardly directed dome member 74 to which the plate 44 may be secured by screws 75, thus forming the top of lubricant and refrigerant reservoir 32. Passages 76 may join the lower portion of the reservoir 32 formed by the plate 71 with the upper portion of the reservoir 32 formed by the plate 51 and dome member 74.

The lower plate 71 may be provided with a cylindrical extension 77 which forms the lower shaft bearing casing. A bearing member 78 may be placed in the extension 77. A thrust bearing 79 may be threadingly engaged with the interior of the extension 77 and the end of the casing may be sealed by plate 80 to which the lubricant pipe 56 may be connected.

A dome shaped casing 81 may be placed around the refrigerant liquefying unit. The casing 81 may be removable. It may be made axially removable by providing radial extensions 82 on the lower plate member 71. The casing 81 may be secured to the radial extensions 82 by means of screws 83 preferably in radial threaded engagement with the members 82. By removing the screws 83, the casing partition may be removed

axially from the refrigerant liquefying unit. The casing 81 causes the air which is circulated by the fan to pass over the receiver 35, the condenser 33 and the lubricant cooling coil 55 as well as other parts of the refrigerant liquefying unit. The air may pass out through an opening 85 to the top of the casing 81. A combined stand and auxiliary casing 86 may be placed underneath the pumping mechanism. The stand 86 may be provided with downwardly directed legs 87 in order to provide air passages 88. The upper end of the stand 86 may include a perforated plate 89 provided with air openings 90, thus providing a continuous air passage from the air inlets 88 through the openings 90, up through the casing 81 and out through the opening 85.

The stand 86 may support the pumping mechanism in any suitable manner. Thus the plate 89 may be provided with upwardly extending cylindrical cups 91 adapted to receive the lower ends of the rubber blocks 70. The condenser 33 and the receiver 35 may be placed under the plate 89 in the stand 86 and the connections to the pumping machinery may be made through openings provided in the plate 89.

The pipe 23 may be connected through a fitting 92 provided with a spring pressed check valve 93. The reservoir 32 may be connected with the condenser 33 by means of a needle valve controlled fitting 94. The motor casing 95 may be provided with the necessary openings, one of which is shown at 96 for permitting a certain amount of air to circulate through the motor parts.

The pumping mechanism may be slightly modified as shown in Figs. 6 to 9 inclusive. The shaft 40a may correspond with the shaft 40 in the mechanism heretofore described. The refrigerant may enter the pumping mechanism through the inlet 36a and may be discharged through the discharge opening 50a. The vanes 100 may be keyed in an eccentrically mounted rotary member 101, with their outer edges 102 bearing against the inner cylindrical surface 103 of the cylindrical pump casing 104. Springs 105 are placed in cavities 61a which may also constitute the lubricant pumping chambers. Thus the cavities 61a may be connected to the lubricant inlet pipes 52a in the end plates 106 and 107 and may also be connected to the lubricant outlet pipe 54a in the end plates 106 and 107. This may be accomplished by providing suitable semi-circular grooves 110 and 111 which may be connected with the appropriate pipes 54a and 52a, respectively. It will thus be seen that the vanes 100, while they are moving outwardly, suck the lubricant through the pipes 52a into the grooves 111 and thence into the cavity 61a. Upon the inward movement of the vanes 100 the lubricant in the cavities 61a is forced into the grooves 110 and from thence into the pipes 54a. Thus, in this embodiment, the rotary pumping member is also drivingly connected with a reciprocating lubricant pumping member.

The pump shown in Figs. 6 to 9 inclusive may be placed in a lubricant liquefying unit similar to that shown in Figs. 1 to 5. The lubricant circulated by the lubricant pumps in this modification may be circulated through a cooling coil similar to coil 55, and the lubricant may be forced into bearings 109 through passages 112 and 113. In this embodiment, a resistance may be interposed between the oil discharge from the cooling coil 55 and the reservoir 32, and the passages 112 and 113 are in parallel with the 75

flow of oil through the cooling coil. In this embodiment the oil reservoir 32 may be made by a casing separate from the pump chamber.

While the form of embodiment of the invention as herein disclosed constitutes a preferred form, it is to be understood that other forms might be adopted, all coming within the scope of the claims which follow.

What is claimed is as follows:

- 10 1. A motor-compressor unit comprising a casing in which a compressor is sealed in fluid-tight relationship, a motor stator supported exteriorly of and connected to said casing, a drive shaft passing through a stuffing box in said casing, said shaft having a driving connection with said compressor in said casing and supporting a motor rotor exteriorly of said casing in operative relationship to said stator, lubricated bearing means for supporting said shaft and extending a sufficient longitudinal contact along said shaft and being of a nature to align said shaft, means positively circulating lubricant to said lubricated bearing means, the entire lubricated bearing means being within said sealed casing and forming the sole bearing support for said shaft.
- 15 2. A motor-compressor unit comprising a casing in which a compressor is sealed in fluid-tight relationship, a motor stator supported exteriorly of and connected to said casing, a drive shaft passing through a stuffing box in said casing, said shaft having a driving connection with said compressor in said casing and supporting a motor rotor exteriorly of said casing in operative relationship to said stator, lubricated bearing means for supporting said shaft and extending a sufficient longitudinal contact along said shaft and being of a nature to align said shaft, means positively circulating lubricant to said lubricated bearing means, the entire lubricated bearing means being within said sealed casing and forming the sole bearing support for said shaft and a fan driven from said shaft.
- 20 3. A motor-compressor unit comprising a casing in which a compressor is sealed in fluid-tight relationship, a lubricant sump in said casing, a motor stator supported exteriorly of and connected to said casing, a drive shaft passing through a stuffing box in said casing, said shaft having a driving connection with said compressor in said casing and supporting a motor rotor exteriorly of said casing in operative relationship to said stator, lubricated bearing means for supporting said shaft and extending a sufficient longitudinal contact along said shaft and being of a nature to align said shaft, means positively circulating lubricant to said lubricated bearing means, the entire lubricated bearing means being within said sealed casing and forming the sole bearing support for said shaft, said bearing means being lubricated from said sump.
- 25 4. In a motor-compressor unit, a one piece frame member having an annular recess at one side, a shaft journaled in said frame member and having ends projecting at each side of said frame member, said shaft having a reduced portion, a shaft seal cavity within said frame member, shaft seal means housed in said cavity surrounding said reduced portion and having a portion cooperating with the shoulder formed by said reduction in shaft size, an eccentric on said shaft,
- 30 a one piece cylinder block projecting into said recess and positioned thereby and forming a cylindrical chamber concentric with said shaft in radial alignment with said eccentric, end means closing said cylindrical chamber, an impeller mounted on said eccentric and operating in said cylindrical chamber, inlet and outlet ports for said chamber, a divider block between said ports, means forming with said frame member a lubricant and high pressure refrigerant discharge reservoir, means driven by said shaft for circulating lubricant from said reservoir through said seal cavity and to the bearing surface between said shaft and said frame, said outlet port discharging into said reservoir, a first passage in said frame member for returning the circulating lubricant to said reservoir, a second passage in said frame member through which compressed refrigerant leaves said compressor, and a motor drivingly connected to said shaft.
- 35 5. In combination, a one piece frame member having an annular recess at one side, a shaft seal cavity within said frame at the opposite side, a shaft journaled in said frame member, shaft seal means within said cavity and carried by said frame member through which said shaft passes, rotary compressor mechanism carried by said frame member and driven by said shaft, said compressor mechanism including a one-piece cylinder member having a portion projecting into said recess and positioned thereby, means surrounding said cylinder member cooperating with said frame member forming a high pressure refrigerant and lubricant chamber, an oil pump driven by said shaft for circulating lubricant to the shaft seal cavity and to the bearing surface between said shaft and said frame, and a passage in said frame member for returning excess lubricant from said bearing surface to said chamber, the outlet of said discharge passage being disposed above said bearing surfaces and above the lubricant level in said chamber whereby an adequate supply of lubricant is provided for the entire bearing surface between said shaft and said frame.
- 40 6. In combination, a substantially circular compressor frame, a shaft journaled directly in said frame and having ends projecting beyond both sides of said frame, said frame having an integral portion forming an enlarged chamber adjacent one end of said shaft, a running seal for said shaft within said chamber, an eccentric on said shaft, said frame having an annular recess remote from said running seal, a block having a cylindrical chamber concentric with said shaft, said block having a portion fitting within said recess and positioned thereby, means carried by said frame member for completing said cylindrical chamber, means cooperating with said frame member forming a lubricant reservoir in which said block is at least partially submerged, an impeller mounted on said eccentric and operating in said cylindrical chamber, inlet and outlet ports for said cylinder, a divider block between said ports, and means for pumping lubricant from said reservoir to said shaft seal, said frame member having a lubricant passage joining said reservoir and said chamber facilitating the housing and circulation of lubricant.

ROBERT M. GETCHELL. 70
